BEVERAGE COOLER OR SIMILAR ARTICLE

James R. Reichow, Edina, Minn., assignor to The Cornelius Company, Anoka, Minn., a corporation of Minnesota

Filed June 22, 1964, Ser. No. 80,496

Term of patent 14 years

(Cl. D2—3)

FIG. 1 is a front perspective view of a beverage cooler, showing my new design.

FIG. 2 is a rear perspective view thereof.

FIG. 3 is another front perspective view thereof, with the hinged draft arm shown in dispensing position.

FIG. 4 is a rear elevational view thereof.

The dominant features of my design reside in the full line portions.

I claim:

The ornamental design for a beverage cooler or similar article, substantially as shown and described.
